[57] CLAIM

The ornamental design for a copy machine controller, substantially as shown and described.

DESCRIPTION

FIG. 1 is a front and top perspective view of a copy machine controller showing my new design;

FIG. 2 is a right side elevational view thereof, the left side being a mirror image thereto;

FIG. 3 is a cross-sectional view thereof as taken from line 3—3 of FIG. 4;

FIG. 4 is a front elevational view thereof;

FIG. 5 is a top plan view thereof, the bottom being substantially flat and unornamented;

FIG. 6 is a rear elevational view thereof.
